UNITED STATES PATENT OFFICE.

HERMAN EHRLICH, OF CHICAGO, ILLINOIS.

PRESSER FORM.

Application filed May 22, 1922. Serial No. 562,748.

To all whom it may concern:

Be it known that I, HERMAN EHRLICH, a citizen of the United States, and a resident of the city of Chicago, in the county of Cook 5 and State of Illinois, have invented certain new and useful Improvements in a Presser Form; and I do hereby declare that the following is a full, clear, and exact description of the same, reference being had to the accompanying drawings, and to the numerals of reference marked thereon, which form a part of this specification.

This invention relates primarily to presser forms or heads for clothes pressing machinery.

It is an object of this invention to provide a presser head that is so designed as to impart the proper shape to a garment, especially coats and the like.

It is a further object of this invention to provide a presser head adapted to be sustained in spaced relation to its supporting buck and which is provided upon its under surfaces with a heat conducting grid so arranged as to distribute the heating medium such as steam over the entire surface thereof and conduct the heat from the heating chamber to the pressing surface.

It is a further object of this invention to provide an upper buck for the upper presser head or form that prevents the condensation of the steam from passing through the latter and to provide a lower buck that suitably co-operates with the lower presser form.

With these and other objects in view, which will become more apparent in the following description and disclosures in the drawings, this invention comprises the novel mechanism and combination of parts herein- 40 after described and more particularly pointed out and defined in the appended claims.

In the accompanying drawings, which illustrate a preferred embodiment of this invention, and in which similar reference numerals refer to similar features in the different views:

Figure 1 is an elevational view of a clothes pressing machine to which my invention has been applied.

Figure 2 is a transverse section through the two presser heads in operative position for pressing a garment upon an enlarged scale.

Figure 3 is a top plan view of the upper buck upon an enlarged scale.

Figure 4 is a section on the line 4—4 of Figure 3.

Figure 5 is a section on the line 5—5 of Figure 3.

Figure 6 is a section on the line 6—6 of Figure 3.

Figure 7 is a top plan view of the lower buck taken upon the line 7—7 of Figure 8 upon an enlarged scale as to Figure 1.

Figure 8 is a section on the line 8—8 of Figure 7.

Figure 9 is a section on the line 9—9 of Figure 8.

Figure 10 is a section on the line 10—10 of Figure 8.

Figure 11 is a bottom plan view of the lower presser head or form illustrating the grid formation upon an enlarged scale.

Figure 12 is a top plan view of the upper presser head or form upon an enlarged scale.

As shown on the drawings:

In referring now to the drawings, it will be noted that in Figure 1 there has been illustrated a clothes pressing machine to which my invention has been applied. The machine comprises a frame having a stationary platform or support 1 for sustaining the lower buck and presser form and an overhanging swingable arm 2 for supporting the upper buck and presser form attached thereto for swinging the same downwardly into contact with the lower one. The swingable arm 2 is adapted to be operated by a pedal 3 which is suitably connected to a depending arm 4 extending from the arm 2. The particular operating mechanism or machine of this type, however, is well known and forms no part of this invention except in so far as it may co-operate therewith.

This invention concerns itself with the presser forms and the bucks to which they are attached. The upper buck and presser form, which are illustrated in Figures 3 to 6 and 12, will first be described. In the form 5 is designed to fit over a coat and to properly shape the same during the pressing operation. To this end, the form, which may be constructed of sheet metal or any suitable material, is provided with an upwardly extending curved or concave portion 6, designed to fit over the shoulders, and a slightly depressed portion 7 designed to press inwardly the back of the coat just below the shoulder blades, and a slightly raised por-

tion 8 designed for flaring the coat at the hips, and a downwardly sloping portion 9 designed for properly shaping the tail of the coat. The parts just described extend longitudinally; the transverse contour of the form 5 is slightly arcuate or concave as shown in Figures 5 and 6 to properly shape the garment transversely. The head or form

5 is perforated throughout its lower area for 10 the passage of steam, and the upper surface is provided with a grid in the form of a plurality of disconnected or broken webs 10 which extend radially from the central part of the plate for diffusing the steam and for 15 conveying the heat from the heating chamber to the surface of the form which contacts the garments.

The upper presser form or head 5 is adapted to be bolted or secured to an upper 20 hollow buck 11 with the webs 10 contacting the lower surface of said buck, said buck being provided with a steam heated chamber 12, which radiates the heat through the grid on the presser form 5. The chamber 25 12 extends substantially coextensive with the area of the buck 11 and steam is admitted to said chamber 12 through the inlet pipe 13. From the chamber 12, the steam passes up through the elevated U-shaped pipe 14 which is provided with a valve 15 and which connects with a passage 30 16 formed in a raised ridge on the top of the buck 11. The passage 16 extends downwardly at both ends into communication 35 with the space formed by the grid on the presser head 5, where it will be diffused by the grid and penetrate the apertures in the forming head for steaming the garment that is being pressed. It should be noted 40 that the passage 16 constitutes a raised path through which the steam must travel on its way into contact with the forming head 5, the prior condensation of the steam will settle in the chamber 12, so that dryer steam 45 will pass through the raised passage 16 and into contact with the apertured presser head, whereby the objectionable saturation 50 of the pressing pads is avoided. The condensed steam may pass through the outlet pipe 17 through which the steam in the upper buck may escape. The concave surface of the upper presser head may be covered with a pressing pad 18 of any suitable construction.

55 The lower presser head 19 has an upper contour provided with a raised portion 6, a depression portion 7, a slightly raised portion 8 and a sloping tail portion 9, which extend in a longitudinal direction similar 60 to the upper presser form, the transverse surface thereof being curved or convex, the contour of this lower presser head being designed to fit the contour of the upper presser head, as is shown in Figure 2. The 65 lower surface of this presser head is formed

with a grid comprising the radially extending and broken webs similar to those of the upper presser head for diffusing the steam and also conducting the same from the heat chamber to the surface of the presser head. The lower presser head is also perforated for the passage of steam therethrough.

The lower presser head or form 19 is adapted to be bolted or secured to a lower 75 hollow buck 20 which is provided with a steam chamber 21 communicating with the space between the buck and presser head through the ports 22. The steam is adapted to enter the chamber 21 through the port 23 and escape through the port 24, while the steam and condensation between the presser heads may be exhausted by means of suction through the exhaust port 25. The upper surface of the lower presser form or head is covered with a pressing pad 26 (Fig. 2). This lower buck 20 is adapted to be suitably attached to the support 1 of the machine, while the upper buck 11 is adapted to be suitably attached to the 80 arm 2, and when the arm 2 is swung downwardly the upper presser head will engage over the lower presser head and press and shape any garment that has been placed therebetween. The manner of admitting the 85 steam into the heating chambers in the bucks and controlling the same together with the action of the suction and operation of the machine are well known and need not be described.

100 From the foregoing, it will be apparent that the presser heads involving this invention will not only press the clothes but will also impart the proper shape and style thereto. It should also be noted that by 105 using a heating chamber in which most of the condensation takes place, and from which the lighter and dryer steam passes into contact with the pressing pads, the latter will not become objectionably saturated 110 during the pressing operation.

I am aware that numerous details of construction may be varied through a wide range without departing from the principles of this invention, and I therefore do not purpose limiting the patent granted otherwise than necessitated by the prior art.

I claim as my invention:

1. In a clothes pressing machine, a buck 120 comprising an integral member having a steam chamber, a presser form attached to said buck and having attached grids, said grids contacting said buck to provide a steam distributing chamber, said buck having a raised passage communicating with said distributing chamber, and an elevated pipe connecting said steam chamber and raised passage.

125 2. In a clothes pressing machine, a buck, a presser form having radially extending 130

and broken grids attached thereto with said grids contacting the surface of said buck, said presser form having a raised portion and adjacent depressed portion, a second 5 raised portion of different design from the first raised portion which terminates in a sloping portion.

In testimony whereof I have hereunto subscribed my name in the presence of two subscribing witnesses.

10

HERMAN EHRLICH.
